(No Model.)

J. RAPP.

SIDE HILL PLOW.

No. 300,502.

Patented June 17, 1884.

UNITED STATES PATENT OFFICE.

JOHN RAPP, OF COLLINSVILLE, CONNECTICUT.

SIDE-HILL PLOW.

SPECIFICATION forming part of Letters Patent No. 300,502, dated June 17, 1884.

Application filed March 5, 1884. (No model.)

To all whom it may concern:

Be it known that I, JOHN RAPP, of Collinsville, in the county of Hartford and State of Connecticut, have invented a new and Improved Side-Hill Plow, of which the following is a full, clear, and exact description.

The object of my invention is to provide a side-hill plow of simple and durable construction, and one which may be handled more easily than ordinary plows of this class.

The invention consists in the construction and arrangement of parts, as will be herein-after fully described and claimed.

Reference is to be had to the accompanying drawings, forming part of this specification, in which similar letters of reference indicate corresponding parts in all the figures.

Figure 1 is a side elevation of my improved plow. Fig. 2 is a plan view of the same with one of the handles partly broken away, and with the mold-board shown in reversed position in dotted lines; and Fig. 3 is a sectional plan view on the line *xx*, Fig. 1.

A is the plow-beam, having suitable proportions for strength, and fitted with any approved draft-clevis, *a*, at the front.

B is a shoe securely attached to the beam by a standard, *C*, mortised into the shoe after passing between upright cleats *b b*, fixed to the shoe, and between which cleats the lower forward converging ends of the handles *D* also fit, the handles being also mortised into the bed-plate of the shoe, so that the standard *C* and handles *D* serve firmly to hold the shoe against backward movement, while the shoe-cleats *b b* strengthen their connection with the shoe by serving as lateral braces. From the shoe the handles *D* diverge and pass at each side of the beam *A*, to which they are bolted at *d*, and extend backward and are braced at suitable distance apart by the cross-bar *E*, as shown.

F is the mold-board or share, which is securely bolted to the standard *G*, which may have two or more side extensions, *g g*, to brace and strengthen the mold-board at the back against the strains of use. The standard *G* is pivoted in the shoe *B* at *H*, and by its upwardly-extending journal *I* in the

beam *A*, so that the mold-board *F* may be 50 swung on its pivots *H I* to either side after the beam is swung around, to set the mold-board for cutting both ways on the side hill. I swing the mold-board by a lever, *J*, which is pivoted to the journal *I*, and works over the cross-bar *K*, bolted to the beam *A*, which bar serves as a fulcrum, on which the mold-board may be raised by the lever prior to reversing the mold-board. The mold-board is held in both positions by a hook, *L*, which is 55 hung on a staple or other suitable eye-fastening, *l*, fixed to the standard *C*, and is hooked into eyes or staples *M*, fastened to the back of the mold-board near its opposite edges, as will be understood from the drawings.

In its construction and operation my improved plow is very simple and durable, and may easily be handled without the heavy lifting required in the use of other plows, and my plow may also be used to advantage in 60 level soils.

I am aware that side-hill plows have been heretofore constructed in which the mold-board was secured to a standard pivoted between the beam and a shoe secured below the 65 beam by a standard and the handles; also, that a mold-board pivoted as above has been provided with hinged wings connected to a standard by pivoted links, and I do not desire to claim any such constructions, broadly, as 70 75 my invention.

Having thus described my invention, what I claim as new, and desire to secure by Letters Patent, is—

A side-hill plow consisting of the beam *A* 85 and shoe *B*, connected together by the standard *C* and handles *D*, braces *b*, connecting the handles and standard *C*, staple *l*, secured to standard *C*, and having the hooks *L*, pivoted standard *G*, lever *J*, fulcrum-bar *K*, and mold-board *F*, secured at the center of its rear face 90 to the pivoted standard, and provided with eyes *M* on both sides of its center for engaging said hooks *L*, substantially as set forth.

JOHN RAPP.
